UNITED STATES PATENT OFFICE.

PETER J. BORGER, OF CINCINNATI, OHIO.

IMPROVEMENT IN SAFETY DEVICES FOR HOISTS.

Specification forming part of Letters Patent No. 123,672, dated February 13, 1872.

I, PETER J. BORGER, of Cincinnati, Hamilton county, Ohio, have invented a new and useful Improved Safety Device for Hoists, of which the following is a specification:

Nature and Objects of the Invention.

This is an improvement in the class of hoists whose platform is raised and lowered by a rope or chain; and my invention relates to an improved device, whereby the slackening of the said rope or chain upon the winding-cylinder, consequent on the detention of the platform from any cause or the breakage of the rope, is made effective to stop the rotation of the driving-shaft and its attachments, and thus to prevent the uncoiling and entanglement of the rope and the accidents incident thereto.

General Description with Reference to the Drawing.

Figure 1 is an elevation, and Fig. 2 a partial section of my improved hoisting apparatus, the parts being in their proper relative positions for ordinary use. Figs. 3 and 4 show the same parts in the positions they assume when the rope becomes slackened by the accidental stoppage of the descending platform or other cause.

My driving-pulley A, instead of being keyed fast to the shaft B, revolves loosely upon it, except as it is connected thereto by a spring-pawl, C, which, engaging in a ratchet-wheel, D, that is fast to said shaft, compels the rotation of the shaft and its attached winding-cylinder E when revolved in direction of the arrow, Figs. 1 and 2, as in the act of elevating the platform. When revolved in the contrary

direction, (see Figs. 3 and 4,) the weight of the platform, communicated through the rope G, causes the ratchet D to react against the pawl, so as to keep these two members in gear. H is a gravitating pawl pivoted at h to the frame or other stationary object; and, when liberated by the slackening of the rope, engaging in a ratchet-wheel, I, attached to the shaft B or to the winding-cylinder E, and at all other times held out of gear with said wheel in consequence of its sheave J resting against the rope G.

The instant that the rope G becomes slackened from detention of the descending platform or other cause the gravitating pawl H drops into the ratchet-wheel J and instantly arrests the motion of the shaft B and its attachments, including the winding-cylinder E, and thereby prevents the uncoiling of the rope.

In place of the driving-pulley A I may employ a cog-wheel.

Claim.

I claim herein as new and of my invention—
The combination of the loose driving-pulley or wheel A attached to shaft B by spring-pawl C and ratchet D, and the drum E and ratchet-wheel I keyed on said shaft with the gravitating pawl H, the whole constructed and arranged as herein shown and described, for the purposes specified.

In testimony of which invention I hereunto set my hand.

PETER J. BORGER.
